Jas. A. Richmond

Attorney

UNITED STATES PATENT OFFICE.

ARTHUR E. DAVENPORT, OF MAYWOOD, ILLINOIS, ASSIGNOR TO OIL PRODUCTS APPLICATION CO., OF MAYWOOD, ILLINOIS, A CORPORATION OF ILLINOIS.

SIGHT-PRIME AND DRAINAGE INDICATOR FOR GASOLINE PUMPS.

Application filed September 27, 1928. Serial No. 308,856.

Most States have laws regulating the operating conditions of filling stations. For example, Ohio requires a device to show that the pump is primed and that the products have not leaked back past the foot-valve, and Massachusetts requires some indication that the hose is draining.

Hence, objects of my invention are to provide for full compliance with such and other State requirements; and the nature of the invention consists in the provision of a gauge on top of the delivery pipe of a gasoline pump in lieu of the usual vacuum breaker, and which will afford positive indication of normal prime and drainage conditions; the device embodying a sight tube which passes gasoline from the regulation inlet pipe, a positive "gas level" and provision whereby vacuum breaking is utilized to cause a stream of bubbles to rise in the gauge, to show the customer that gasoline is flowing, until the hose is actually drained.

The annexed drawing is a view principally in section of a device constructed in accordance with my invention.

Referring thereto, 5 is an element, which may be a casting, having fluidways 6 and 7 whereof the former receives the usual gas inlet connection 8 and whereof the fluidway 30 7 receives the usual hose connection. The top of element 5 is of generally flat disc form pierced with openings coextensive with said respective fluidways and having an upstanding marginal rim or flange 9. In short, it is formed to constitute the lower head of a sight tube or glass cylinder 10, which is completed by an upper head 11, the assemblage being rigidly secured as a unit by a central tie rod 12.

40 A tube 13 coextensive with the fluidway 7 rises to the normal gas level about midway of the cylinder which is etched, as at 14, or formed with some other appropriate symbol to indicate the normal level, that is to say the level at which the gasoline should be found before and after pumping operation.

The upper head is formed with a valve-way 15 to accommodate a disc valve 16 having a

seat 17 and accessible upon removal of a nut 18. A conduit 19 connects the space below the valve with an air chamber 20 ported to atmosphere through a cover 21. And air passing the valve is conducted via passage 22 to a tube 23 extending to near the bottom of the sight glass and from which it escapes upwardly through the gasoline in the form of bubbles.

Evidently when the pump is operating the valve 16 will be held to its seat and no bubbling will ensue. When, however, the pumping operation is completed the vacuum breaking function is inaugurated by the lifting of the valve and the resultant suction of air into the cylinder; that is to say, as soon as the hose starts to drain a stream of air bubbles will be emitted by the tube 23, and they will continue to rise to the surface of the gasoline in the sight glass until the hose is completely drained.

Having described my invention, I claim:

1. A gasoline pump delivery unit, including a sight glass, inlet and outlet elements, respectively, leading to and from said sight glass, means within the glass for indicating normal liquid level, and means for admitting air to the sight glass above said level thereby to permit liquid flow, said air admission means providing for passage of air in bubble form upwardly through the visible liquid to indicate liquid flow.

2. A gasoline pump delivery unit, including a sight glass, a liquid inlet and a liquid outlet, a pipe rising in the sight glass and closing the inlet against the delivery thereby to maintain a normal level of liquid, means on the sight glass visibly to indicate normal liquid level, means to admit air to the sight glass above the liquid level to permit liquid flow, and means whereby the air is caused to rise through the body of liquid in the sight glass, thereby to provide by its bubble characteristic an indication visible through the sight glass of liquid flow.

In testimony whereof I affix my signature.

ARTHUR E. DAVENPORT.
